ATTORNEYS

UNITED STATES PATENT OFFICE.

JAMES F. MULHOLLAND, OF COLUMBUS, OHIO.

TOY BALLOON.

Application filed January 11, 1923. Serial No. 612,125.

To all whom it may concern:

Be it known that I, James F. MULHOLLAND, a citizen of the United States of America, residing at Columbus, in the county of Franklin and State of Ohio, have invented certain new and useful Improvements in Toy Balloons, of which the following is a specification.

My present invention relates generally to 10 toys and more particularly to toy balloons of that nature which are designed to be sold in knocked-down deflated condition for inflation and erection by the purchaser, my primary object being the provision of a highly 15 interesting device of this nature which embodies a minimum number of parts and of which the parts are such as to permit of easy quick erection and of mutual cooperation, when erected, to maintain the integrity of the toy as a whole.

In the accompanying drawing which illustrates my present invention and forms a part of this specification,

Figure 1 is a front elevation,

Figure 2 is a side elevation,

Figure 3 is a horizontal section through the car or basket taken substantially on line 3-3 of Figure 2,

Figure 4 is a fragmentary side view showing the overlapping ends of the strip of material forming the car or basket,

Figure 5 is a plan view of the cut-out blank for the car or basket,

Figure 6 is a plan view of the cut-out disk forming the base of the car or basket.

Figure 7 is a side view showing the ring with the bag holding connections depending therefrom,

Figure 8 is a fragmentary side view of a portion of the car or basket illustrating a slightly modified form,

Figure 9 is a sectional side view illustrating the connection of one of the bag holding members according to the form shown in Figure 8, and

Figure 10 is a view similar to Figure 4 illustrating a slightly modified construction in respect to the connection of the overlapping ends of the basket strip,

Referring now to these figures my invention proposes a toy balloon including a spherical inflated bag 10 which, in the event of inflation with air, may be carried by a top ring 11 and which in case of inflation with gas so that the toy as a whole is lighter

than air, may be controlled by a depending flexible connection 12 as seen in Figure 1 preferably having a finger engaging ring 13. The bag 10 in its inflated condition as shown in Figures 1 and 2 is held in connection with, and projects partially into the upper open end of, a circular car or basket 14 to which it is connected by a series of depending flexible attaching connections 15 whose upper ends are connected in a series to the beforementioned ring 11 and whose lower ends are connected to the upper edge of the car or basket 14 at spaced points around the latter so that the series of connections thus embrace the bag 10 and hold the latter in connection with the car or basket 14.

The car or basket 14 is formed from an elongated rectangular strip of material 16 as shown in Figure 5 and for the purpose of connection with the lower ends of the attaching members 15 this strip of material may have along its upper edge a series of openings 17 through which the lower ends of the several attaching members may be tied. This particular connection may however be varied to the extent of providing the strip 16 with openings of slightly different shape, as for instance openings 17^a as seen in Figure 8 within the illustrated portion of a strip 16^a, each opening communicating with an inverted V shaped notch 17^b whereby each of the flexible connections one of which is indicated at 15^a in Figure 9 may have a lower knotted or otherwise enlarged end 15^b capable of extension through the opening 17^a and of engagement within the notch 17^b.

In the formation of the car or basket 14, the strip 16 of Figure 5 is bent to circular form with overlapping connected ends 18 which as seen in Figures 4 and 5 may have registering apertures 19 for the reception of any suitable form of pin fasteners or, overlapping ends as indicated at 18^a in Figure 10 and may be connected by clips 20 embracing the upper and lower portions of said overlapping ends.

The strip 16 in the formation of the car or basket 14 is preferably cut-out by means of a die operation from a section of material sufficiently flexible for the purpose and with cut-out portions 21 in a series therealong which in the completed form of the car or basket represent windows. The strip is also

cut out with series of figures 22 within the cut-out portions 21 and upstanding from the lower edges of these cut-out portions, the figures being thus of the same material and 5 readily flexible to an extent sufficient to permit certain thereof to be bent outwardly at an angle as indicated at 22^a in Figure 1 so as to represent these particular figures as looking downwardly from the balloon.

10 The strip 16 is also cut out with openings 23 at spaced points along its lower edge and a base is also cut out, preferably by a die operation, in the form of a disk 24 as seen particularly in Figures 3 and 6, with 15 a central opening 25 through which the flexible control connection 12 may depend and with radially outstanding extensions 26 the latter of which are adapted to project through the lower openings 23 of the car 20 or basket so that when the latter is secured in the circular form the base or disk 24 will be locked in place and it is to be noted that this base or disk being connected within the car or basket presents a circular peripheral 25 edge against the inner surface of the car or basket at the lower end of the latter and thus cooperates with the bag 10 in preventing ready collapse or distortion of the car or basket.

30 The series of flexible attaching members 15, before described, may be accompanied by an elongated flexible flag holding connection 27 as seen in Figures 2 and 7, intermediate the ends of which a flag 28 may be 35 secured, this connection being preferably extended to the lower edge of the car or basket as in Figure 2.

The car or basket may also have an anchor 29 depending therefrom by virtue of a flexible connection 30 permanently attached to the strip 16, the latter of which it will be 40 observed from Figures 1 and 2 may have its outer surface suitably embellished or ornamented after formation by printing, lithographing and the like.

45 In the manufacture of my improved toy balloon it is contemplated that the bag 10 will be supplied purchasers in deflated condition along with a strip 16 and detached base disk 24 from which it is obviously an 50 easy quick operation for the purchaser to perform and complete the car or basket and, after inflation of the bag 10 assemble the toy complete by extending the flexible attaching members around the bag and securing the same to the car or basket and it will be 55 observed that according to my improved construction the purchaser is supplied with but four major parts, namely the bag, the 60 strip 16 from which the car or basket is formed, the base or disk 24 and the ring 11 with its several attaching connections or members 15 so that there is thus little likelihood of loss or misplacement of any of the 65 parts and but simple instructions need be

supplied in order that the toy as a whole may be successfully erected and thereafter maintained.

I claim:

1. A toy balloon including a spherical 70 inflated bag, a car or basket consisting of a strip of material bent into circular form and open at its upper end to receive a portion of the bag therein, means extending around the bag and engaging the upper edge 75 of the basket to hold the balloon in place, and a disk detachably mounted within the lower portion of the car or basket forming the base thereof and cooperating with the balloon in holding the car or basket in its 80 circular form.

2. A toy balloon including a spherical inflated bag, a car or basket consisting of a strip of material bent into circular form and open at its upper end to receive a portion of the bag therein, means extending around the bag and engaging the upper edge 85 of the basket to hold the balloon in place, and a disk detachably mounted within the lower portion of the car 90 or basket forming the base thereof and cooperating with the balloon in holding the car or basket in its circular form, said strip of material constituting the car or basket having overlapping connected ends 95 and having openings therearound adjacent to its lower edge, and said disk having radially outstanding extensions projecting through the said openings.

3. A toy balloon including a spherical 100 inflated bag, a car or basket consisting of a strip of material bent into circular form and open at its upper end to receive a portion of the bag therein, a disk detachably mounted within the lower portion of the car or basket, forming the base thereof and 105 cooperating with the bag in holding the car in its circular form, said strip of material having overlapping connected ends and a series of openings therethrough adjacent 110 to the upper edge thereof, and a ring having a series of flexible attaching members extending therefrom for connection through the said openings of the said strip and embracing the bag to hold the latter in place. 115

4. A toy balloon including a spherical inflated bag, a car or basket consisting of a strip of material bent into circular form and open at its upper end to receive a portion of the bag therein, a disk detachably mounted within the lower portion of the car or basket, forming the base thereof and 120 cooperating with the bag in holding the car in its circular form, said strip of material having overlapping connected ends and a series of openings therethrough adjacent to the upper edge thereof, and a ring having a series of flexible attaching members extending therefrom for connection through the said openings of the said strip and 125 130

embracing the bag to hold the latter in place, said openings of said strip having V-shaped recesses adjoining the same and said flexible attaching members having enlarged lower ends to extend through the openings and for engagement in the recesses.

5. A toy balloon including a spherical inflated bag, a car or basket open at its upper end to receive a portion of the bag, flexible

10 means embracing the bag and connected to the upper edge of the car or basket to hold

the bag in connection therewith, said car or basket consisting of a strip of material having overlapping connected ends and having cut-out portions representing members 15 and figures within said cut-out portions up-standing from the lower edges thereof, said figures being flexible and adapted to be bent outwardly for the purpose described.

In testimony whereof I have affixed my 20 signature.

JAMES F. MULHOLLAND.
